SELF-LOADING DEVICE FOR SHAKER CONVEYORS

John H. Holstein, Chicago, Ill., assignor to Goodman Manufacturing Company, Chicago, Ill., a corporation of Illinois

Application June 21, 1946, Serial No. 678,378

14 Claims. (Cl. 198—14)

1

This invention relates to improvements in self-loading devices for shaker conveyors of the type utilized for picking up coal, rock or the like from the ground in mines.

The principal objects of my invention are to provide a novel and compact form of draft device mounted beneath the extensible and reciprocating troughs of a shaker conveyor trough line for moving said troughs laterally about a swivel in the trough line and including a single flexible draft member adapted to be secured at its ends at points spaced laterally from opposite sides of said troughs, together with an improved form of power drive means for moving said troughs along said draft member and an improved means for maintaining tension on the slack side of said draft member during movement of the troughs along said draft member and compensating for angular movement of said troughs with respect to said draft member.

This and other objects of my invention will more clearly appear as the following specification proceeds and with reference to the accompanying drawings wherein:

Figure 1 is a top plan view of a loading device constructed in accordance with my invention;

Figure 2 is an enlarged plan view of the forward end of the loading device with certain parts of the extensible and reciprocating troughs broken away and certain parts of the draft device shown in horizontal section;

Figure 3 is an enlarged fragmentary view in side elevation of the loading device with certain parts broken away and certain other parts shown in substantially longitudinal section;

Figure 4 is a fragmentary transverse sectional view taken substantially along line 4—4 of Figure 1;

Figure 5 is a fragmentary transverse sectional view taken substantially along line 5—5 of Figure 1;

Figure 6 is an enlarged fragmentary plan view of the draft device with certain parts broken away and certain other parts shown in substantially horizontal section, in order to show certain details of the drive to the sprockets for moving the loading device along the flexible draft member;

Figure 7 is a fragmentary enlarged detail sectional view showing certain details of one of the clutches for the draft device;

Figure 8 is a fragmentary transverse sectional view taken substantially along line 8—8 of Figure 5; and

Figure 9 is a fluid diagram showing the fluid 55

2

connections for operating the draft device and maintaining tension on the slack side of the flexible draft member.

In the drawings the embodiment of my invention illustrated therein includes generally an extensible trough 10 having a pick-up member or shovel 11 on its forward end, slidably supporting the forward end of said extensible trough on the ground. The rear end of said extensible trough is supported above the ground on a ground-engaging shoe 12 in a manner similar to that shown and described in a prior patent to Ernst R. Bergmann, Re. 21,027, and no part of my present invention so not herein shown or described in detail.

The extensible trough 10 has two bearing plates 13, 13 which extend along its upper outer edges and form a supporting means for the forward end of a reciprocating trough 15 between a pair 20 of vertically spaced supporting and guide rollers 16, 16 mounted on each side of said trough (see Figure 3). Said supporting and guide rollers are mounted on opposite upright sides 17, 17 of a supporting frame 19, projecting above the top of 25 said reciprocating trough. Said supporting frame is secured to and extends forwardly of and across the bottom and upwardly along opposite sides of said reciprocating trough.

The bearing plates 13, 13 are also adapted to 30 be engaged by friction grip blocks 20, 20 of a friction grip feeding device 21, during alternate strokes of the conveyor, for extensibly or retractably moving said extensible trough with respect to said reciprocating trough, or for reciprocably moving said extensible and reciprocating troughs together. Said friction grip feeding device is clearly shown and described in a companion application Serial No. 678,379, filed here-with, and is no part of my present invention so 40 need not herein be shown or described in detail. The reciprocating trough 15 is connected to and reciprocably driven from the shaker conveyor trough line through an articulated trough connection or swivel 23. Said swivel is so arranged as 45 to form a means for controlling lateral movement of said reciprocating and extensible troughs and to permit the continuous flow of material along said reciprocating trough and swivel to the outby end of the trough line, when said reciprocating and extensible troughs are in various 50 positions of lateral displacement with respect to the trough line. Said swivel is no part of my present invention except insofar as it connects the reciprocating trough with the conveyor trough line and forms a pivotal reaction member for

said reciprocating and extensible troughs, so will not herein be shown or described in detail.

The reciprocating trough 15 discharges into and is connected at its rear end to a connecting trough 24 of the swivel 23. Said connecting trough is mounted at its rear end on a shoe 25 and is nested in and pivotally connected to the receiving end of an intermediate trough 26. Said shoe is spaced forwardly from and is pivotally connected to a stationary base 27 for lateral movement with respect thereto along the ground, as in Patent No. 2,347,074, which issued to E. R. Bergmann on April 18, 1944. Said stationary base is adapted to be held in fixed relation with respect to the ground during operation of the conveyor by means of suitable jacks or the like (not shown) interposed between said base and the mine roof.

An elongated supporting and guide frame 29 is connected at its rear end to the shoe 25 for movement therewith about the base 27, and extends beneath the reciprocating trough 15 to a point beyond the forward end thereof. Said frame is held from reciprocation during operation of the conveyor by the shoe 25 and base 27 and forms a non-reciprocating reaction and guide means for the extensible and reciprocating troughs 10 and 15, for laterally moving said troughs with respect to the stationary base 27 of the swivel 23 along a flexible draft member 30, upon lateral movement of said frame.

Two laterally spaced longitudinally extending guide tracks 33, 33 are mounted on and extend along opposite outer sides of the forward portion of the frame 29, and beyond the forward end of said frame and forwardly along opposite sides of a floating frame 31, which forms a forward extension of said frame 29. Said guide tracks have recessed substantially V-shaped engaging faces, which are adapted to be engaged by the V-shaped engaging faces of rollers 35, 35. Said rollers are rotatably mounted on vertical shafts 36, 36, mounted at their ends in bifurcated bracket members 37, 37, extending inwardly from the side walls 17, 17 of the frame 19, for supporting the forward end of said non-reciprocating frame above the ground.

The floating frame 31 is pivotally connected to the forward end of the non-reciprocating frame 29 on transversely extending pivotal pins 40, 40, and is adapted to have floating engagement with the ground at its forward end. Said pivotal pins extend through opposite forward end portions of said non-reciprocating frame and through lugs 41, 41 projecting rearwardly from opposite sides of said floating frame and interleaved by said forward end portions of said non-reciprocating frame. Said floating frame forms a floating support for the draft means for moving the extensible trough 10 and reciprocating trough 15 along the flexible draft member 30, and is so arranged that tension of said draft member will hold the forward end of said frame in engagement with the ground, in the manner shown and described in application Serial No. 640,875, filed by E. R. Bergmann on January 12, 1946, which has matured into Patent No. 2,425,078, August 5, 1947, and no part of my present invention.

The means for moving the extensible and reciprocating troughs along the flexible draft member 30 and for holding said troughs in various fixed positions along said draft member includes two laterally spaced sprocket wheels 42, 42, disposed at opposite sides of the floating frame 31, adjacent its forward end. Said flexible draft

member is herein shown as being a well known form of link chain meshing with and extending laterally from each of said sprockets. The bight of said draft member between said sprockets is engaged by a tension idler 43 disposed rearwardly of said sprockets. Said tension idler is mounted on the end of a piston rod 44 extending from a piston 94 mounted within a fluid cylinder 45, and is urged by fluid under pressure entering the head 10 end of said cylinder in a direction to maintain tension on the slack side of said chain and also to compensate for changes in length of said draft member caused by angular movement of said extensible trough with respect to said chain. 15 One of said sprockets forms a means for moving said frame and troughs along said draft device in one direction while the other sprocket on the slack side of said chain rotates freely. Said sprockets are herein shown as being driven from 20 a fluid motor 51 and the drive to each of said sprockets is substantially the same, with the exception that one sprocket is adapted to be driven in one direction only while the other sprocket is adapted to be driven in a direction opposite to 25 which the first sprocket is adapted to be driven, upon reversal of said motor 51, so the drive to one of said sprockets only will herein be described in detail.

The sprocket 42 is keyed on a vertical shaft 46, 30 journaled at its lower end in a bottom plate 47 of said floating frame and extending upwardly therefrom (see Figure 4). Said shaft is journaled just above the upper side of said sprocket in a bottom wall 48 of a housing and support 35 frame for the gearing, for driving said sprockets 42, 42 from the motor 51. A spur gear 49 mounted in said housing coaxial with said shaft has selective driving connection with said shaft through a jaw clutch 50, which is so arranged as to drive 40 said shaft and sprocket when said motor rotates in one direction and to permit said sprocket to rotate freely when the direction of rotation of said motor is reversed. The jaw clutch 50 includes an enlarged annular formation on the 45 upper end of said shaft which has serrated clutch jaws 54, 54 formed on its top side. Said clutch jaws are adapted to be engaged by corresponding serrated clutch jaws 55, 55 formed in the bottom surface of an inner annular portion 56 of a drive member 57 (see Figure 7). Said drive member 50 is splined on the inner periphery of the rim of the spur gear 49. Said clutch jaws 54 and 55 are so formed that one face extends at a relatively steep angle while the other face extends at a 55 flatter angle. The flat angled faces of said clutch jaws are so inclined that the clutch will disengage itself when the drive member 57 is rotating in a direction to drivingly engage said flat angled faces with each other. The faces of the clutch 60 jaws for the clutch 50, for driving the opposite sprocket 42, are disposed oppositely from the faces of the clutch jaws just described, so that when one sprocket 42 is driven in one direction through its clutch, the clutch jaws for the other sprocket will be driven in a direction to disengage themselves. One sprocket 42 thus serves to 65 swing the loading device in one direction, while the other sprocket serves to swing the loading device in an opposite direction upon reversal of the direction of rotation of the motor 51.

A closure plate 59, secured to the bottom of the rim of said spur gear, closes the hollow inside of said spur gear and is secured thereto. Said closure plate has an open central portion which is 75 journaled on the bottom wall 48 coaxial with the

vertical shaft 46. A spring 60 is interposed between the top of said closure plate and the bottom of said drive member 57, and acts in a direction to disengage the jaws 55 from the jaws 54 and to hold said clutch in a disengaged position. A cylinder 61 extends within the hollow central portion of the enlarged annular upper end of the shaft 46. Said cylinder has a flange 62 projecting laterally from its upper end, which is journaled in a central recessed portion of the drive member 57 on balls 64, 64. Said cylinder is slidably mounted on a piston 65 which projects upwardly therefrom through the spur gear 49. Said piston has an enlarged upper head portion 66, which is detachably secured to a top cover plate 68 for the gear housing. Said piston also has a bearing 70 mounted thereon, just beneath the cover plate 68, which forms a bearing means for the spur gear 49. A fluid passageway extends through said piston in the direction of its axis, for supplying fluid under pressure to said cylinder to cause said cylinder to engage the jaws 55 with the jaws 54 and engage the clutch to drive the vertical shaft 46 and sprocket wheel 42.

The fluid motor 51 is mounted on the bottom plate 47 of the floating frame 39 and has a forwardly extending motor shaft 73 having a spur gear 74 keyed thereon. Said spur gear meshes with and drives a spur gear 75 keyed on the rear end of a longitudinally extending worm shaft 76. Said worm shaft is journaled in opposite walls 77, 78 of the housing and support for the spur gears 49, 49 and has a worm 79 formed integrally therewith. Said worm meshes with and drives a worm gear 80 keyed on a vertical shaft 81. Said vertical shaft is journaled at its lower end in a bearing support 83 and is journaled at its upper end in the cover plate 68, and is herein shown as having a spur gear 84 formed integrally therewith and disposed just beneath said cover plate. Said spur gear 84 drives the spur gears 49, 49 on opposite sides thereof through spur gears 85, 86, one of said spur gears being disposed on each side of said spur gear 84.

When it is desired to swing the extensible trough 10 and shovel 11 to the right, the right-hand clutch 50 may be engaged by supplying fluid under pressure to its associated cylinder 61 through the piston 65, to move said cylinder downwardly along said piston. Fluid under pressure is also supplied to the motor 51 to cause said motor to drive the right-hand sprocket in a direction to cause said sprocket to travel along the chain 30 to the right. At the same time, fluid may be admitted to the head end of the cylinder 45 to engage the tension idler 43 with the bight of the chain 30 between the two sprockets 42, 42 and maintain tension on the slack side of said chain. The less steeply inclined faces of the jaws of the clutch 50 for the left-hand sprocket 42 on the slack side of the chain will be driven in a direction to engage each other. This will tend to disengage said clutch aided by the spring 60 and permit said sprocket to rotate freely. Said spring will then hold said clutch in a disengaged position.

When it is desired to swing the shovel 11 and extensible trough 10 to the left, the clutch for the left-hand sprocket may be engaged by supplying fluid under pressure to its associated cylinder 61, and the direction of rotation of the fluid motor 51 is reversed. Fluid is released from the cylinder for operating the clutch for the right-hand sprocket and said sprocket will be disengaged by engagement of the less steeply inclined faces

of the teeth of its clutch with each other and by the associated spring 60, to permit the right-hand sprocket to rotate freely. The left-hand sprocket will then move said extensible trough and shovel along the chain 30 to the left.

When it is desired to hold the shovel from lateral movement, especially when the apparatus is working along a laterally pitching floor, the two clutches 50 are engaged by their associated cylinders 61, 61, and the valve for supplying fluid to the motor 51 is placed in a neutral position, to hold pressure on both sides of said motor and lock said motor and sprockets from rotation.

The cylinder 45 is mounted intermediate its ends in a bracket 95 abutting and secured to the inner side of an end wall 96, extending across the forward end of the elongated frame 29. Fluid under pressure may be admitted to either end of said cylinder to move the tension idler 43 in a direction to hold the chain 30 under a predetermined tension, or to release tension of said chain when it is desired to move the apparatus or to set it up and secure the free ends of the chain 30 adjacent opposite ribs of the working place.

In the fluid diagram shown in Figure 8, a fluid storage tank 97 is provided to supply fluid to a pump 99. Said fluid storage tank and pump and the motor for driving said pump may be mounted on the stationary base 21 of the swivel 23. A pipe 100 connects said pump with a control valve 101. Said control valve may be of a well known form of series type spool valve of a type similar to that shown in application Serial No. 600,950, filed by W. W. Sloane on June 22, 1945, and no part of my present invention so not herein shown or described in detail. Said valve is arranged to permit fluid to flow therethrough when in a neutral position and to hold pressure in the pipes leading from its pressure ports when in said position, so as to hold pressure in the hydraulic devices operated thereby when desired. Said control valve is connected with opposite sides of the fluid motor 51 through pipe 102 or 103, for supplying fluid under pressure to said motor through either of said pipes, to drive said motor in one direction or another. When said valve is in a neutral position, fluid pressure will be held in the pipes 102 and 103 by said valve and the motor 51 will be hydraulically locked from rotation. A drain pipe 104 connects said motor 51 with a return pipe 105 leading to the tank 97, to return fluid to said tank which may leak by the rotors of said motor.

A relief valve 106 is connected in the pipe 100 and is set to by-pass fluid to the tank 97 upon overload conditions in the pressure line leading from said pump.

A pipe 107 leads from the pipe 100 to supply fluid to operate the grip blocks 20, 20 of the feeder head 21 in the manner clearly shown and described in my aforementioned companion application. Fluid is returned from the grip block operating mechanism to the tank 97 through a return pipe 108.

A control valve 109 for supplying fluid under pressure to either of the cylinders 61, 61 is connected in series with the control valve 101 through a pipe 110. Said control valve may be of a well known form of spool type 4-way control valve. A pipe 111 connects one pressure outlet of said control valve with the right-hand cylinder 61. A pipe 112 connects the other pressure outlet of said control valve with the left-hand cylinder 61. When said valve is in one extreme

position or the other, fluid will be supplied to one cylinder and released from the other, and when said valve is in a central position, fluid will be supplied to apply both clutches simultaneously. Fluid is returned to the tank 97 through a return line 113 connected with a pipe 114 which extends from a relief valve 115 to the return line 105.

A control valve 117 for the cylinder 45 is connected with the pressure pipe 110 on the pressure side of the relief valve 115 through a pipe 118. Said control valve is like the control valve 101 and is connected with the head end of the cylinder 45 to supply fluid under pressure thereto by means of a pipe 119. It is also connected with the piston rod end of said cylinder to supply fluid under pressure thereto by means of a pipe 120.

The relief valve 115 connected in the pipe 110, is set to open upon excessive pressures in the cylinders 61, 61 and the cylinder 45. Said relief valve also permits the piston rod 44 to move inwardly within the cylinder 45, to relieve tension on the chain 30, when tension on said chain exceeds a predetermined value, to permit the tension idler 43 to yield and compensate for varying tensions on said chain.

The valves 101 and 109 may be connected to operate together so that when fluid is supplied to operate the right-hand clutch, the fluid motor 51 will rotate in one direction, and when fluid is supplied to operate the left-hand clutch, the direction of said motor will be reversed. Also, when the valve 109 is in a position to supply fluid under pressure to operate both clutches, the valve 101 will be in position to hold pressure on both sides of the motor 51. When this condition arises, the sprockets 42, 42 are locked from rotation by means of said motor, which is hydraulically locked, to positively hold the shovel 14 in fixed relation with respect to both ribs of the working place.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a shaker conveyor, a reciprocating trough, an extensible trough mounted for extensible or retractible movement with respect to said reciprocating trough, a flexible feeding member extending transversely beneath said troughs and adapted to be fixed at its ends at points spaced laterally from opposite sides of said troughs, means disposed beneath said extensible and reciprocating troughs for moving said troughs along said flexible feeding member and feeding the forward end of said extensible trough laterally, and means engaging said flexible feeding member for maintaining tension on the slack side of said flexible feeding member during movement of said trough therealong.

2. In a shaker conveyor, a swivel, a reciprocating trough extending from said swivel and movable thereabout, an extensible trough having a shovel on its forward end and mounted for extensible or retractible movement with respect to said reciprocating trough, a flexible feeding member extending transversely beneath said troughs and adapted to be secured at its ends at points spaced laterally from opposite sides of said

troughs, power means mounted beneath said extensible and reciprocating troughs for rotation about an upright axis, said power means having operative engagement with said flexible feeding member for feeding said extensible trough and shovel laterally along said flexible feeding member about said swivel, and other means having yieldable engagement with said flexible feeding member and operable to exert a predetermined pressure thereon to maintain tension on the slack side of said flexible feeding member during movement of said extensible trough along said flexible feeding member about said swivel.

3. In a shaker conveyor, a swivel, a reciprocating trough extending from said swivel and movable thereabout, an extensible trough having a shovel on its forward end and mounted for extensible or retractible movement with respect to said reciprocating trough, a flexible feeding member extending transversely beneath said trough and adapted to be secured at its ends at points spaced laterally from opposite sides of said trough, power means mounted beneath said extensible and reciprocating troughs for rotation about an upright axis, for feeding the forward end of said extensible trough laterally along said flexible feeding member about said swivel, and other means having engagement with said flexible feeding member and operable to exert a predetermined pressure thereon to maintain tension on the slack side of said flexible feeding member during movement of said extensible trough therealong including a cylinder and piston having operative engagement with said flexible feeding member.

4. In a shaker conveyor, a swivel, a reciprocating trough extending from said swivel and movable thereabout, an extensible trough having a shovel on its forward end and mounted for extensible or retractible movement with respect to said reciprocating trough, a flexible feeding member extending transversely beneath said troughs and adapted to be secured at its ends at points spaced laterally from opposite sides of said troughs, power means mounted beneath said extensible and reciprocating troughs and having engagement with said flexible feeding member for moving said troughs along said flexible feeding member including two laterally spaced sprockets rotatable about vertical axes, a motor, a geared drive connection between said motor and said sprockets for selectively driving said sprockets including a separate clutch for each sprocket, said clutches being arranged to connect one of said sprockets with said motor to move said extensible trough in one direction along said flexible feeding member and to connect the other of said sprockets with said motor when the direction of rotation of said motor is reversed, to move said extensible trough along said flexible feeding member in an opposite direction, and a compensating sheave engaging the bight of said flexible feeding member between said sprockets, and movable in a direction to maintain tension on the slack side of said flexible feeding member and to compensate for differences in length of said flexible feeding member caused by angular movement of said extensible trough with respect to said flexible feeding member.

5. In a shaker conveyor, a swivel, a reciprocating trough extending from said swivel and movable thereabout, an extensible trough having a shovel on its forward end and mounted for extensible or retractible movement with respect to said reciprocating trough, a flexible feeding

member extending transversely beneath said troughs and adapted to be secured at its ends at points spaced laterally from opposite sides of said trough, power means mounted beneath said extensible and reciprocating troughs and having engagement with said flexible feeding member for moving said troughs along said flexible feeding member including two laterally spaced sprockets rotatable about vertical axes, a motor, a geared drive connection between said motor and said sprockets for selectively driving said sprockets including a separate clutch for each sprocket, said clutches being arranged to connect one of said sprockets with said motor to move said extensible trough in one direction along said flexible feeding member and to connect the other of said sprockets with said motor when the direction of rotation of said motor is reversed, to move said extensible trough along said flexible feeding member in an opposite direction, and a compensating cylinder extending longitudinally of said extensible trough, said compensating cylinder having a sheave extensible therefrom and engaging the bight of said flexible feeding member between said sprockets, and urged in a direction by fluid under pressure within said cylinder to maintain tension on the slack side of said cable and operable to compensate for differences in length of said cable caused by angular movement of said extensible trough about said swivel with respect to said flexible feeding member.

6. In a self-loading device for shaker conveyors, a reciprocating trough, an extensible trough having a shovel on its forward end and mounted for extensible or retractible movement with respect to said reciprocating trough, a flexible chain disposed beneath said extensible and reciprocating troughs and adapted to be fixed at its ends at points spaced laterally from opposite sides of said troughs, two laterally spaced sprockets mounted beneath said extensible trough and having engagement with said chain for moving said extensible and reciprocating troughs about a fixed point disposed rearwardly of said reciprocating trough, and a compensating sheave engaging the bight of said chain between said sprockets for maintaining tension on the slack side of said chain and compensating for differences in length of said chain caused by angular movement of said extensible and reciprocating troughs with respect to said chain.

7. In a self-loading device for shaker conveyors, a reciprocating trough, an extensible trough having a shovel on its forward end and mounted for extensible or retractible movement with respect to said reciprocating trough, a flexible chain disposed beneath said extensible and reciprocating troughs and adapted to be fixed at its ends at points spaced laterally from opposite sides of said troughs, two laterally spaced sprockets mounted beneath said extensible trough and having engagements with said chain for moving said extensible and reciprocating troughs about a fixed point disposed rearwardly of said reciprocating trough, a reversible fluid motor, a geared drive connection from said motor to said sprockets for driving one of said sprockets when said motor is rotating in one direction and for driving the other of said sprockets when the direction of rotation of said motor is reversed, including a separate clutch for each of said sprockets and selectively operable to drive either of said sprockets from said motor, depending upon the direction of rotation of said motor, and positively disengaging the sprocket on the slack side of said chain from said

motor and permitting it to run free, when the control means for said clutch for said sprocket on the slack side of the chain is in a released position, and a compensating sheave engaging the bight of said chain between said sprockets and urged in a direction to maintain tension on the slack side of said chain and to compensate for differences in length of said chain caused by angular movement of said reciprocating and extensible troughs with respect to said chain.

8. In a self-loading device for shaker conveyors, a reciprocating trough, an extensible trough having a shovel on its forward end and mounted for extensible or retractible movement with respect to said reciprocating trough, a flexible chain disposed beneath said extensible and reciprocating troughs and adapted to be fixed at its ends at points spaced laterally from opposite sides of said troughs, two laterally spaced sprockets mounted beneath said extensible trough and having engagement with said chain for moving said extensible and reciprocating troughs about a fixed point disposed rearwardly of said reciprocating trough, a reversible fluid motor, a geared drive connection from said motor to said sprockets for driving one of said sprockets when said motor is rotating in one direction and for driving the other of said sprockets when the direction of rotation of said motor is reversed, including a separate clutch for each of said sprockets and selectively operable to drive either of said sprockets from said motor, depending upon the direction of rotation of said motor, and positively disengaging the sprocket on the slack side of said chain from said motor and permitting said sprocket to run free when the control means for said clutch for said sprocket on the slack side of the chain is in a released position, a compensating fluid cylinder extending longitudinally of said reciprocating and extensible troughs, and having a piston movable therein, a sheave connected with said piston and extensible from said cylinder upon movement of said piston therealong, said sheave having engagement with the bight of said chain between said sprockets and urged in a direction to maintain tension on the slack side of said chain and to compensate for differences in length of said cable caused by angular movement of said reciprocating and extensible troughs with respect to said chain.

9. In a self-loading device for shaker conveyors, a reciprocating trough, an extensible trough having a shovel on its forward end and mounted for extensible or retractible movement with respect to said reciprocating trough, a flexible chain disposed beneath said extensible and reciprocating troughs and adapted to be fixed at its ends at points spaced laterally from opposite sides of said troughs, two laterally spaced sprockets mounted beneath said extensible trough and having engagement with said chain for moving said extensible and reciprocating troughs about a fixed point disposed rearwardly of said reciprocating trough, a reversible fluid motor, a geared drive connection from said motor to said sprockets for driving one of said sprockets when said motor is rotating in one direction and for driving the other of said sprockets when the direction of rotation of said motor is reversed, including a separate clutch for each of said sprockets and selectively operable to drive either of said sprockets from said motor, depending upon the direction of rotation of said motor, and positively disengaging the sprocket on the slack side of said chain from said motor and permitting

said sprocket to run free when the control means for said clutch for said sprocket on the slack side of the chain is in a released position, fluid pressure actuated means selectively operable to move either or both of said clutches to an engaged position, valve means for supplying fluid under pressure to said motor to operate said motor in reverse directions, said valve means being arranged to block the flow of fluid from opposite sides of said motor, to lock said motor from rotation when said valve is in a neutral position, to permit said motor to hold both of said sprockets from rotation when said clutches are both engaged, to hold said reciprocating and extensible troughs in a fixed lateral position with respect to the working face, and a compensating sheave engaging the bight of said chain between said sprockets and urged in a direction to maintain tension on the slack side of said chain and to compensate for the differences in length of said chain caused by angular movement of said reciprocating and extensible troughs with respect to said chain.

10. In a self-loading device for shaker conveyors, a reciprocating trough, an extensible trough having a shovel on its forward end and mounted for extensible or retractable movement with respect to said reciprocating trough, a flexible chain extending beneath said extensible and reciprocating troughs and adapted to be fixed at its ends at points spaced laterally from opposite sides of said troughs, two laterally spaced sprockets mounted beneath said extensible trough and having engagement with said chain for moving said extensible and reciprocating troughs about a fixed point disposed rearwardly of said reciprocating trough, a reversible fluid motor, a geared drive connection from said motor to said sprockets for driving one of said sprockets when said motor is rotating in one direction and for driving the other of said sprockets when the direction of rotation of said motor is reversed, including a separate clutch for each of said sprockets and selectively operable to drive either of said sprockets from said motor, depending upon the direction of rotation of said motor, and positively disengaging the sprocket on the slack side of said chain from said motor and permitting said sprocket to run free when the control means for said clutch for said sprocket on the slack side of the chain is in a released position, a compensating cylinder extending longitudinally of said reciprocating and extensible troughs, and having a piston movable therein, a sheave connected with said piston and extensible from said cylinder upon movement of said piston therealong, said sheave having engagement with the bight of said chain between said sprockets and urged in a direction to maintain tension on the slack side of said chain and to compensate for differences in length of said chain caused by angular movement of said reciprocating and extensible troughs with respect to said chain, valve means for admitting fluid under pressure to said cylinder, and a relief valve permitting the release of fluid from said cylinder and movement of said sheave in a direction to relieve tension on said chain when tension on said chain exceeds a predetermined value.

11. In a self-loading device for shaker conveyors, a reciprocating trough, an extensible trough having a shovel on its forward end and mounted for extensible or retractable movement with respect to said reciprocating trough, a flexible chain disposed beneath said extensible and

reciprocating troughs and adapted to be fixed at its ends at points spaced laterally from opposite sides of said troughs, two laterally spaced sprockets mounted beneath said extensible trough and having engagement with said chain for moving said extensible and reciprocating troughs about a fixed point disposed rearwardly of said reciprocating trough, a reversible fluid motor, a geared drive connection from said motor to said sprockets for driving one of said sprockets when said motor is rotating in one direction and for driving the other of said sprockets when the direction of rotation of said motor is reversed, including a separate one way clutch for each of said sprockets and selectively operable to drive either of said sprockets from said motor, depending upon the direction of rotation of said motor, and positively disengaging the sprocket on the slack side of said chain from said motor and permitting said sprocket to run free when the control means for said clutch for said sprocket on the slack side of the chain is in a released position, fluid pressure actuated means selectively operable to move either or both of said clutches to an engaged position, valve means for supplying fluid under pressure to said motor to operate said motor in reverse directions, said valve means being arranged to block the flow of fluid from opposite sides of said motor, to lock said motor from rotation when said valve is in a neutral position, to permit said motor to hold both of said sprockets from rotation when their associated clutches are engaged and hold said reciprocating and extensible troughs in a fixed lateral position along said chain, a compensating cylinder having a piston movable therein, a sheave connected with said piston and extensible from said cylinder upon movement of said piston therealong, said sheave having engagement with the bight of said chain between said sprockets and urged in a direction to maintain tension on the slack side of said chain and to compensate for differences in length of said chain caused by angular movement of said troughs with respect to said chain, valve means for admitting fluid under pressure to either end of said cylinder, and a relief valve permitting the release of fluid from said cylinder and movement of said sheave in a direction to relieve tension from said chain when tension on said chain exceeds a predetermined value.

12. In a device for laterally feeding the extensible trough of a shaker conveyor about a swivel in a conveyor trough line, a frame having connection with said swivel at its rear end and extending along and having engagement with opposite sides of said extensible trough, two laterally spaced sprockets mounted on the forward end of said frame, a motor mounted on said forward end of said frame, drive connections from said motor to said sprockets for driving one of said sprockets, in one direction, and the other of said sprockets in an opposite direction upon reversal of said motor, said sprocket which is not being driven by said motor being freely rotatable, a flexible chain engaging said sprockets and adapted to be fixed at its ends at points spaced laterally from opposite sides of said troughs, and a compensating sheave for holding said chain in engagement with said sprockets and maintaining tension on the slack side of said chain and compensating for differences in length of said chain caused by angular movement of said extensible trough with respect to said chain.

13. In a device for laterally feeding the extensible trough of a shaker conveyor about a

swivel in a conveyor trough line, a frame having connection with said swivel at its rear end and extending along and having engagement with opposite sides of said extensible trough, two laterally spaced sprockets mounted on the forward end of said frame beneath said extensible trough, a motor mounted on said forward end of said frame, drive connections from said motor to said sprockets for driving one of said sprockets in one direction, and the other of said sprockets in an opposite direction upon reversal of said motor, said sprocket which is not being driven by said motor being freely rotatable, a flexible chain engaging said sprockets and adapted to be fixed at its ends at points spaced laterally from opposite sides of said troughs, a compensating cylinder mounted in said frame and extending longitudinally thereof, a sheave extensible from said cylinder upon the admission of fluid under pressure to said cylinder, said sheave having engagement with the bight of said chain between said sprockets for holding said chain in engagement with said sprockets, and maintaining tension on the slack side of said chain and compensating for differences in length of said chain caused by angular movement of said trough with respect to said chain.

14. In a device for laterally feeding the extensible trough of a shaker conveyor about a swivel in a conveyor trough line, a frame having connection with said swivel at its rear end and extending along and having engagement with opposite sides of said extensible trough, two laterally spaced sprockets mounted on the for-

ward end of said frame, a flexible chain engaging said sprockets and adapted to be fixed at its ends at points spaced laterally from opposite sides of said troughs, a compensating sheave for holding said chain in engagement with said sprockets and maintaining tension on the slack side of said chain and compensating for differences in length of said chain caused by angular movement of said extensible trough with respect to said chain, a reversible fluid motor mounted adjacent the forward end of said frame, a geared drive connection from said motor to said sprockets for driving one of said sprockets when said motor is rotating in one direction and for driving the other of said sprockets when the direction of rotation of said motor is reversed including a separate clutch for each of said sprockets, fluid pressure actuated means selectively operable to move either or both of said clutches to an engaged position, said clutches being so arranged as to positively disconnect the sprocket on the slack side of said chain from said motor, to permit said sprocket to run free when fluid is released from the fluid pressure means for operating its associated clutch, valve means for supplying fluid under pressure to said motor to operate said motor in reverse directions, said valve means being operable to hydraulically lock said motor from rotation, to permit said motor to hold both of said sprockets from rotation upon engagement of both of said clutches, to hold said extensible trough in a fixed lateral position with respect to the working face.

JOHN H. HOLSTEIN.
